PORTABLE GAS DETECTOR OR THE LIKE

Howard M. Canterbury, 6306 Schevers,
Houston, Tex. 77017

Filed Dec. 20, 1965, Ser. No. 250

Term of patent 14 years

(Cl. D52—6)

FIG. 1 is a perspective view from the front, top and one side of a portable gas detector embodying my new design;

FIG. 2 is a perspective view from the back, bottom and other side of the detector; and

FIG. 3 is a front elevational view of the detector.
I claim:

The ornamental design for a portable gas detector or the like, substantially as shown.
